UNITED STATES PATENT OFFICE.

BERT L. MONESMITH, OF CRESCE, IOWA.

SHIPPING DEVICE.

1,085,285.

Specification of Letters Patent.

Patented Jan. 27, 1914.

Application filed July 9, 1913. Serial No. 778,158.

To all whom it may concern:

Be it known that I, BERT L. MONESMITH, a citizen of the United States, residing at Cresco, in the county of Howard and State 5 of Iowa, have invented certain new and useful Improvements in Shipping Devices, of which the following is a specification, reference being had to the accompanying drawings.

10 This invention comprehends certain new and useful improvements in shipping devices and has for its primary object to provide a device for protecting eggs, fruit, explosives, and other fragile articles while 15 loaded in cars and preventing explosion, breakage, or other damage to the articles.

Another object is to provide a device of 20 this character which may be readily employed in cars of the type now in general use and which may be securely fastened against the articles packed in the car, to retain the articles in proper position during transportation.

25 A further object is to provide a device of this character which may be readily mounted upon suitable tracks within the car and moved to proper position to securely hold the freight against movement during transportation.

30 A still further object is to provide a device of this character formed of several sections, which may be either permanently secured in position in the car or mounted upon the tracks therein and temporarily secured 35 at any desired position within the car.

A still further object is to provide novel supporting means and securing means for the several sections of the device.

40 A still further object is to provide a device of this character with the sections formed in such manner as to act as cushions against the freight, thereby absorbing all shocks incident to the sudden jerks or movement of the car.

45 A still further object is to generally improve and simplify the construction and operation of devices of this character and increase the efficiency of the same.

With the above and other objects in view, 50 my invention consists in certain novel constructions, combinations, and arrangements of parts to be hereinafter more fully described, claimed, and illustrated in the accompanying drawings in which,

55 Figures 1 and 2 are diagrammatic views

showing the relative positions of the parts of the invention; Fig. 3 is a plan view of one of the lock strips to be secured to the floor and side of the car; Fig. 4 is a front elevational view of one of the adjustable extension means for one of the end members; Fig. 5 is a side elevational view of the same; Fig. 6 is a vertical cross sectional view through one of the tracks to be secured to the ceiling of the car showing in elevation the wheels mounted thereon and the adjustable extension members by means of which the wheels are carried and which are secured to the inner or movable members; Fig. 7 is a side elevational view thereof; Fig. 8 is a detail sectional view of the lower portion of one of the parts, showing the manner in which the frame cushions are secured thereto; Fig. 9 is an enlarged elevational view of one of the end members; Fig. 10 is a side elevational view of the same; Fig. 11 is an enlarged side elevational view of the lower portion of one of the movable members, showing the manner in which the locking bolt is mounted and engaged in the lock strip; and Fig. 12 is a view at right angles to Fig. 11, showing the lower portion of the bolt engaged in the lock strip with the lock strip in cross section.

Referring more specifically to the drawings in which similar reference characters designate corresponding parts throughout the several views, 1 designates the end members which are composed of vertical strips 2 and horizontal strips 3 positioned across and connected to the vertical strips 2 at equally spaced distances, as clearly shown in Fig. 1, from the lower ends of said vertical strips 2 to about half the length of the vertical strips of each end 1. To the upper end of each outer vertical strip 2 of each end 1, is secured an upwardly directed channel iron 4 within which is adjustably engaged the extension member 5 having its upper end perforated, as shown at 6, to receive the hook 7 formed on the lower end of the depending arm of the angle iron 8, the horizontal arm of which is adapted to be secured to the ceiling of the car by screws 9 or other suitable means. The extension strip 5 is adjustably secured in the channel iron 4 by the set screw 10 carried by the channel iron 4 and engaged through the longitudinal slot 11 in the extension strip. It will therefore be seen that each end member 110

1 is properly secured in position in the car, preferably at one end of said car.

Outwardly of one face of the frame or lower portion of each end member 1 is a frame cushion member 12 which is formed of short vertical strips 13 and horizontal strips 14 positioned across and secured to the same and the frame cushion member 12 is connected with the lower or frame portion of the member 1 by means of the helical cushion springs 15 which serve to retain the frame or cushion 12 in spaced relation to the lower or frame portion of the member 1. The movable members 16 which are adapted to be secured against the freight after the same has been properly packed in the end of the car and against the frame cushion 12 of the member 1, are of substantially the same construction as the members 1 with the exception of the upper portions thereof, said members 16 each having a frame cushion 17 secured to one face thereof by the helical cushion springs 18, and the frames 17 being of the same construction as the frame cushions 12. The outer or long vertical strips 16' of each movable member 16 have channel irons 19 secured thereon near their upper end and adjustable suspension strips 20 adjustably secured in the channel irons 19 by means of the set screws 21. The upper end of each adjustable suspension strip 20 is forked, as shown at 22, and within the upper forked end is mounted the shaft 23 upon which are mounted the spaced wheels 24 engaged upon the rails 25 of the track 26. The track 26 is substantially of U-shaped form and has its central portion secured to the ceiling of the car, as shown at 27, and extends longitudinally of the same, while the edges of the track are bent outwardly, as shown at 28, and have the rails 25, previously mentioned, formed upon their upper faces.

Each of the movable members 16 is locked in proper position upon the track 26 by means of a cam wheel 29 carried by each adjustable suspension member 20 and rigidly mounted upon the shaft 30 extended through one of the forked or separated portions of the member 20 and adapted for engagement with the under face of one of the edges 28 of the tracks 26, said cam wheel 29 being normally retained in operative position to prevent movement of the wheels 24 in one direction upon the rails 25, by means of the lever 31 mounted at its upper end upon the outwardly extended end of the shaft 30. It will be understood that the lever 31 is mounted in such manner that the weight of the depending end thereof will cause said lever and the shaft 30 to rotate sufficiently to bring the cam wheel 29 into binding engagement with the under face of the track edge 28. By raising the lower end of the lever, however, the cam

wheel 29 may be readily disengaged from the track edge 28 to allow the upper end of the movable members 16 to be moved in either direction.

The sides and bottom of each movable member 16 are held against movement by means of the bolts 32 mounted in suitable bearings 33 and having their inner ends bent at right angles, as shown at 34, to limit outward movement of said bolts, while the outer ends of said bolts are adapted for engagement in the proper bolt openings 35 in the main portions of the bolt holding strips 36 which are secured at proper points along the floor and sides of the car, as clearly shown in Figs. 11 and 12, said strips being secured in position by the screws 37 or other suitable means and the notches 38 being formed in the bottom and sides of the car beneath each of the openings 35.

From the foregoing, it will be readily seen that after crates of eggs, fruit, or the like have been packed against the frame cushion 12 at one end of the car, one of the movable members 16 is moved up against the crates and properly secured in position by means of the cam wheels carried by the adjustable extensions 20 thereof and by the bolts 32, as previously described, it being understood that the movable members 16 are mounted upon the tracks 26 in such manner that the frame cushions 17 carried thereby are toward the ends of the car while the frame cushions 12 carried by the member 1 are toward the center of the car. It will also be understood that as the tracks 26 stop short of the ends of the car, the movable members 16 may be removed from the ends of the tracks when not in use or at any other times desired and it will also be understood that when desired, the movable members 16 may be reversed and secured in position against the opposite sides of freight packed in the central portion of the car or between the center and one end thereof.

It will be seen that when this device is employed for holding in place eggs, fruit, or other fragile articles of freight during shipment, and the frame cushions 12 and 17 engaged against opposite sides of said articles, the cushion springs of the frame cushions 12 and 17 will serve to absorb all shocks incident to sudden movement or jerking of the car, and thereby preventing breakage, explosion, or other damage to the articles.

While I have shown the preferred embodiment of my invention, it will be understood that, if desired, the end members 1 may be mounted in the same manner as the movable members 16 instead of being permanently secured at the ends or through certain points in the car, and other minor changes in the details of construction and arrangement of the parts may be made within the scope of the appended claims without

departing from the spirit of my invention or sacrificing any of the advantages of the same.

What I claim is:—

- 5 1. A device of the class described comprising the combination with a car, of stationary members mounted in the ends of the car, freight article engaging members carried by the stationary members, cushion means between the freight article engaging members and the stationary members, movable members within the car, tracks for said movable members, freight article engaging members carried by the movable members, cushion means between the last mentioned freight article engaging members and the movable members, and means for locking the movable members in adjusted position longitudinally of the car.
- 10 2. A device of the class described comprising the combination with a car, of stationary members mounted in said car, freight article engaging members carried by the stationary members, cushion means between the freight article engaging members and the stationary members, tracks extending longitudinally of the car, movable members mounted on said tracks and adapted for movement toward and away from the stationary members, freight article engaging members carried by the movable members, cushion means between the last freight article engaging members and the movable members, means for locking the movable members against movement upon the tracks, and means for locking the lower portions of said movable members against movement.
- 15 3. A device of the class described comprising the combination with a car, of a stationary member mounted in the ends of the car, freight article engaging members carried by the stationary member, cushion means between the freight article engaging members and the stationary members, tracks extending longitudinally of the car, movable members mounted on said tracks and adapted for movement toward and away from the stationary members, freight article engaging members carried by the movable members, cushion means between the last freight article engaging members and the movable members, means for locking the movable members against movement upon the tracks, and means for locking the lower portions of said movable members against movement.
- 20 4. In testimony whereof I hereunto affix my signature in the presence of two witnesses.
- 25 BERT L. MONESMITH.
- 30 Witnesses:
CHARLES PEYLE,
GEORGE E. STORY.

car, wheels carried by the suspension members and engaged with the tracks, means carried by the suspension members and adapted for engagement with the tracks to prevent movement of the wheels upon the same, and means for preventing movement of the bottom and sides of the movable members.

car, wheels carried by the suspension members and engaged with the tracks, means carried by the suspension members and adapted for engagement with the tracks to prevent movement of the wheels upon the same, and means for preventing movement of the bottom and sides of the movable members.

car, wheels carried by the suspension members and engaged with the tracks, means carried by the suspension members and adapted for engagement with the tracks to prevent movement of the wheels upon the same, and means for preventing movement of the bottom and sides of the movable members.
